UNITED STATES PATENT OFFICE

FRANK H. RICHTERKESSING, OF LOUISVILLE, KENTUCKY, ASSIGNOR TO THE CHEATHAM ELECTRIC SWITCHING DEVICE CO. AND NACHOD AND UNITED STATES SIGNAL CO., BOTH OF LOUISVILLE, KENTUCKY

ELECTRIC SWITCH AND SIGNAL SYSTEM

Application filed March 24, 1928. Serial No. 264,439.

My invention relates to electric switch and signal systems and has particular application to automatic electro-magnetic setting of the switch point of an electric railway track in 5 different positions in accordance with the approach of a car under "power on" or "power off" respectively, and operating a signal simultaneously therewith that would display indications to warn the traffic of a desired car 10 movement.

One object of my invention is to produce a system that is operated automatically from a car.

Another object of my invention is to provide an improved signal system to display indications simultaneously with the operation of a track switch when the course of the car is to be other than a continuation of its normal or straight ahead course.

20 A still further object of my invention is to provide a safe control system embodying relays and circuits of much simpler nature than heretofore used in combination with electric track switch and signal operation. This feature is highly desirable for production and service. This additional apparatus is connected to a well known standard switch throwing apparatus and the operation of the signal is produced simultaneously at the instant of the energization of the circuits and apparatus for throwing the switch point to the curved course.

My invention resides in a new and novel combination construction and relation of the 35 various electrically operated switches, circuits, and other parts hereinafter more fully described and disclosed in the drawings.

In the drawings accompanying my specification:

40 Fig. 1 is a schematic drawing showing the arrangement of parts and circuits when the system is in a normal condition. The drawing includes the modified arrangement of circuits usually found in an electrically operated track switch system; under such circumstances, however, the switch tongue may be in either of its operable positions.

45 Fig. 2 is a schematic drawing showing the general arrangement of circuits when the signal system is not intended to be used with an

existing switch operating device, but is intended for use at locations where signal indications are to be displayed for the traffic when the car turns or backs as is the case of the switch movements.

55 Fig. 3 is a sectional drawing of the normally closed trolley contactor showing the general arrangement of the parts as used in the circuits described and disclosed in Fig. 2.

60 Fig. 4 is a schematic drawing showing the general arrangement of circuits usually found in an electrically operated car and which are taken care of in the operation of my invention.

65 My invention is intended primarily for use with those cars which are operated by means of the overhead trolley wheel or current collector W mounted on a car by means of a trolley pole T1, although it may be operated by cars in which current is supplied thereto by other methods. Most cars are equipped with heaters H H, lights L, air compressors F, which are connected between the trolley pole and ground as shown in Fig.

70 4. The cars are equipped with operating motor M M, and a controller C C, therefor, which is under the control of the car operator. When the controller is closed current will flow through the motor M M, and in this position, I term "power on", and when the controller is open no current will flow through the motors and this position, I term "power off".

75 The controller C C, does not in any way control the current flowing through the apparatus H H, L, and F, which I term the auxiliary car current. The current flowing through the motors flows to ground G. I have arranged the system herein described so that the track switch will be operated to the "straight ahead" position when the collector W engages the trolley contactor P with "power off" and the track switch will be thrown to the "curve" position when the current collector engages the system using "power on".

80 This operation of the track switch, however, may be reversed by merely transposing the connections of the track switch operating solenoids and it is believed that this change is evident to those skilled 85 in the art.

90 95 100

In the system shown in Fig. 1, the letter D represents a trolley wire or conductor. Positioned adjacent the trolley conductor is a pan or trolley contactor P, provided with 5 two contact members E and C, which are usually parallel and normally insulated from each other. The member E is electrically connected to the trolley conductor D at all times, and the member C is normally insulated, but is electrically connected thereto 10 when the collector W engages the pan or trolley contactor P. The contact members E and C are so related to the trolley conductor that when the current collector engages the 15 contact members, it will be out of engagement with the trolley conductor and remain so until it has passed out of engagement with the pan or trolley contactor P. Such arrangement of the contact members and conductor is well known to those skilled in the 20 art.

The switch circuit includes relay X, and track switch N which is provided with two solenoids SN and CN, each having an electrical connection to the ground G through 25 the common conductor 7.

The solenoids are provided with a reciprocating plunger J which is drawn inwardly when the solenoid CN is energized and is 30 drawn outwardly when the solenoid SN is energized. The plunger J is connected to the switch tongue O by means of the connecting link K.

The electrically operated normally open 35 relay X is provided with an operating coil KL and switch arm A1. The coil KL is mounted on a magnet core although a moving plunger may be substituted for the magnet core as is well known in the art. One terminal of the coil KL is connected to the contact member E of trolley contactor P by wire E1, and the other coil terminal is connected to the trolley conductor D by wires D1 and D3. It will also be noted that one coil terminal of coil KL is a common connecting point 40 for wires D1, D2, and D3, D2 being a feed wire of the signal circuit. The switch arm A1 is normal in its free state; that is, not influenced by any magnetic flux, and rests 45 against the normally closed contact 2, which is a back contact of relay X, and is connected through wire 3 to solenoid SN of track switch N. When the armature A1 is raised or attracted, as is the case when the coil KL is 50 energized, it is brought into contact engagement with contact 1, which is a front contact of relay X, and is connected through wire 4 to solenoid CN of track switch N. It will also 55 be noted that contact 1 is a common connecting point for wires 4 and 8, wire 8 being a ground return control wire for the signal circuit.

Relay Y, which is the controlling relay of 60 the signal circuit, is equipped with an operating coil L and an armature A2. One ter-

70 minal of the coil L of relay Y is connected by wire 10 to resistor 9 through wire 8, wire 4 to solenoid CN of track switch N, the other terminal of coil L is connected through wire 11 to contact strip 20 of trolley contactor R. The armature A2 of relay Y is normally affected by the energized coil L of relay Y and is raised into contact engagement with contact 13, which is a front contact of relay Y. When the coil L of relay Y is deenergized, 75 the armature A2 releases and makes contact engagement with contact 14 which is a back contact of relay Y. The releasing of the armature A2 closes the signal circuit and the signal S is displayed; a circuit being completed from trolley conductor D, through wire D1, wire D2, resistor 21, wire 22, armature A2, back contact 14 of relay Y, wire 15, lamp 16, wire 17, lamp 18, wire 19 to ground G. Lamps 16 and 18 are so arranged in a 80 housing that they illuminate an opaque sign while they are burning. It should also be noted that one terminal of coil L of relay Y is a common connecting point for wires 11 and 12, wire 12 connecting the coil terminal 85 of relay Y with the front contact 13 of relay Y.

The signal S of Fig. 1 is usually a sign 90 painted with the desired lettering either "Car turns" or "Car backs", such as may be the requirements of a given locality and the lamps 16 and 18 are arranged with suitable reflectors that illuminate the sign while they are burning. In some cases it might be desired 95 that the sign could not be read at any time when the signal lamps 16 and 18 are not burning. In this case an opaque glass is painted on the rear with the desired lettering and the lamps placed behind. In addition to the lamps 16 and 18 illuminating the sign, they 100 also display red color light signal indications.

If the current collector W engages the 105 trolley contactor P with "power off", the contact members E and C will be electrically connected and of the same potential as the trolley conductor D, as the contact member is electrically connected by trolley conductor D at all times, by wire D1 connecting the trolley conductor D and low resistance coil KL, and wire E1 connecting the other terminal to coil 110 KL and contact member E. Coil KL has a 115 very low resistance and usually consists of 10 or 12 turns of #6 copper wire. Relay X is a current selective relay; that is, a very heavy current must pass through its operating coil KL before it can affect its armature A1. As soon as the contact member C is 120 electrically connected to the trolley conductor, through the manner just mentioned, current will flow from the trolley conductor D, through wire D1, coil KL, wire A1, contact member E, current collector W, contact member C, wire C1, armature A1, back contact 2 of relay X, wire 3, solenoid SN of track switch N, wire 6, wire 7, to ground G, and the 125

track switch mechanism will operate the track switch to the "straight ahead" position as is arranged and described heretofore. It should be noted that the current for the operation of the track switch solenoid SN is taken through coil KL of current selective relay X, but as the current of this circuit is relatively small comparative to the minimum currents drawn by cars in the "power on" position, this current flowing through the coil KL will have no operative affect on the armature A1 of relay X. Current will continue to flow to solenoid SN as long as the current collector W engages the trolley contactor P with "power off", however, as soon as the current collector W disengages the trolley contactor P, the current of the track switch solenoid circuit SN will be broken at the trolley contactor P. It should be noted that with this car operation the signal control circuit was not affected, therefore, the signals were not displayed and the car was given the "straight ahead" route.

If the current collector initially engages the pan with "power on", the coil KL of relay X will be instantly energized and pick up armature A1 into engagement with contact 1. As soon as armature A1 engages contact 1, current will flow from the trolley conductor D through wire D1, coil KL of relay X, wire E1, contact member E of trolley contactor P, current collector W, contact member C of trolley contactor P, wire C1, armature A1, front contact 1, wire 4, solenoid CN of track switch N, wire 5, wire 7 to ground G, energizing the solenoid CN and throwing the switch to the "curve" position. If it should be in the curved position, however, no change will occur in the position of the switch and it will be held in this position. Incident to the energization of solenoid CN of track switch N, the coil L of the signal operating relay Y is shunted through front contact 1, wire 8, resistor 9, wire 10 by putting positive potential on both terminals on coil L, and the coil becomes deenergized and releases its armature A2. The releasing of the armature A2 opens the normally closed stick circuit of the coil L feeding from the trolley conductor D through wire D1, wire D2, resistor 21, wire 22, armature A2, front contact 13, wire 12, wire 11, coil L of relay Y, wire 10, resistor 9, wire 8; wire 4, solenoid CN of track switch N, wire 5, wire 7 to ground G, and the signal circuit is closed by armature A2 falling into contact engagement with back contact 14, closing a circuit feeding from the trolley conductor D, through wire D1, wire D2, resistor 21, wire 22, armature A2, back contact 14 of relay Y, wire 15, lamp 16, wire 17, lamp 18, wire 19 to ground G, and the signal S is displayed as heretofore described, to warn the vehicle traffic against the movement which the car is about to make.

The car having selected and obtained its

desired direction proceeds and takes the "curved" route passing a trolley contactor R a predetermined clearance distance around the curved section of the track, where the signal S is restored to normal and the vehicle traffic permitted to proceed. The current collector of the car engages trolley contactor R, making contact engagement with contact strip 20, feeding from the trolley conductor D, through the current collector W, contact strip 20 of trolley contactor R, wire 11, coil L of relay Y, wire 10, resistor 9, wire 8, wire 4, solenoid CN of track switch N, wire 5, wire 7 to ground G, and the armature A2 is affected and brought into contact engagement with front contact 13 of relay Y wherein the normal stick circuit is established to retain the armature A2 in a raised position, the circuit being established from trolley conductor D, through wire D1, wire D2, resistor 21, wire 22 armature A2, front contact 13, wire 12, wire 11, coil L of relay Y, wire 10, resistor 9, wire 8, wire 4, solenoid CN of track switch N, wire 5, wire 7 to ground G. As was described the current for the operation of relay Y was taken through the solenoid CN of track switch N, but it should be understood that the current in this circuit is very small, always less than, say one ampere and will have no effect on the solenoid CN that would cause an operation of the track switch, as a very heavy current is required in this solenoid circuit before a switch operation can occur.

To sum up the operation of the system, if the car operator desires to go "straight ahead" he sets his controller to "power off", with the intention of coasting past the trolley contactor P. As soon as the current collector W engages the trolley contactor P, relay X will select the track switch solenoid that will affect an operation to the "straight ahead" position, and no traffic signal will be displayed.

If the car operator desired to take the "curve", he will turn his controller to "power on" with the intention of passing the contactor drawing power. When the current collector W engages the trolley contactor P with "power on", relay X will operate and the track switch solenoid will be selected that will effect a switch operation for the "curved" position, and incident to this operation a signal will be displayed to warn the traffic of the operation that the car is about to make. After the car has completed its desired operation and passed around the curve, the signal is restored and the traffic is permitted to proceed in its usual manner.

In the system shown in Fig. 2, the letter D represents a trolley wire or conductor. Positioned adjacent the trolley conductor is located a trolley contactor Q, provided with a contact strip 24 which is normally connected to the trolley conductor D by wire D1, and a normally closed contact 23 insulated from the

trolley conductor D, but normally connected thereto by contact engagement with strip 24 and wire D1. When the current collector W engages the trolley contactor, the contact strip 24 is deflected and the contact 23 is opened and remains so until the collector W has passed out of engagement with the trolley contactor Q. A more complete description and detail of the trolley contactor Q will be hereinafter disclosed in the description of Fig. 3.

Relay Y, which is the controlling relay of the signal circuit, is equipped with an operating coil L and an armature A2. One coil terminal of the coil L of relay Y is connected by wire 10 to resistor 9, through wire 8 to ground G. The other terminal of coil L is connected through wire 11 to contact strip 20 of trolley contactor R. The armature A2 of relay Y is normally affected by the energized coil L of relay Y and is raised into contact engagement with contact 13, which is a front contact of relay Y. When the coil L of relay Y is deenergized, the armature A2 releases and makes contact engagement with contact 14 which is a back contact of relay Y. The releasing of the armature A2 closes the signal circuit and the signal S is displayed; a circuit being completed from trolley conductor D, through wire D1, contact strip 24 of trolley contactor Q, normally closed contact 23 of trolley contactor Q, wire D2, resistor 21, wire 22, armature A2, back contact 14 of relay Y, wire 15, lamp 16, wire 17, lamp 18, wire 19 to ground G. The lamps 16 and 18 are so arranged to either illuminate color light signals or a sign as is disclosed in the description of Fig. 1.

Fig. 3 is a sectional view of the normally closed trolley contactor Q. In the figure, D is the trolley wire or conductor. Positioned adjacent the trolley conductor are strips 24 and 24A which are flexibly connected to the rigid bracket U by flexible strip springs S and S1 respectively. B and B1 are spring spacer blocks connecting S2 and S1 to the bracket U. When the contactor Q is not engaged by a current collector, the strips S2 and S1 make contact engagement with the contact piece 23 which is electrically connected to wire D2 by connecting bolt 23A and securing nuts M, being insulated from the supporting bracket U and the supporting backbone 26 by the insulating tube T and wood support beam 25. When the contactor Q is engaged by a current collector, the strips 24 and 24A are deflected and S2 and S1 are brought out of engagement with contact piece 23 as indicated by the dot-dash lines of the drawing.

The system shown in Fig. 2 is intended primarily for points where cars have backing movements or where they turn across highway intersections. In such cases a current selective arrangement would not be re-

quired as all cars would produce a similar indication. The signal controlling relay Y of this system is normally energized; that is, its armature A2 is held in a raised position under the influence of the operating coil L, by a normally closed circuit feeding from the trolley conductor D, through wire D1, contact strip 24 of trolley contactor Q, contact 23, wire D2, resistor 21, wire 22, armature A2 of relay Y, front contact 13 of relay Y, wire 12, wire 11, operating coil L of relay Y, wire 10, resistor 9, wire 8 to ground G. When a trolley car passes contactor Q, its current collector W engages the contactor and strip 24 is deflected, normally closed contact 23 is opened and remains so until the current collector W has passed out of engagement with the trolley contactor Q. The opening of contact 23 opens the normally closed stick circuit of relay Y and the armature A2 of relay Y releases and retains the said circuit open, by the opening of a circuit established between armature A2 and front contact 13 of relay Y. When the armature A2 is released it makes contact engagement with back contact 14 of relay Y and a circuit is established feeding from trolley conductor D, through wire D1, contact strip 24 of contactor Q, contact 23 of contactor Q, wire D2, resistor 21, wire 22, armature A2 of relay Y, back contact 14 of relay Y, wire 15, lamp 16, wire 17, lamp 18, wire 19 to ground G, and the signal is displayed as heretofore described to warn the vehicle traffic against the movement which the car is about to make.

The car having completed its desired switch movement under the protection of the signal, passes a predetermined point wherein the signal is restored to normal and the vehicle traffic permitted to proceed. At this point contactor R is located, which affects the restoring operation through the contact engagement of the current collector W, trolley conductor D and contact strip 20 of trolley contactor R, a circuit being established from the trolley conductor D, through the current collector W, contact strip 20 of trolley contactor R, wire 11, coil L of relay Y, wire 10, resistor 9, wire 8 to ground G. The completion of this circuit energizes the coil L of relay Y and the armature A2 is raised opening the signal circuit at back contact 14 and completing the stick circuit at front contact 13 of relay Y, feeding from trolley conductor D, through wire D1, contact strip 24 of trolley contactor Q, contact 23, wire D2, resistor 21, wire 22, armature A2, front contact 13, wire 12, wire 11, coil L of relay Y, wire 10, resistor 9, wire 8 to ground G.

To sum up the operation of this system, a car entering a zone wherein it is necessary to make a switch movement, passes a trolley contactor and establishes a signal circuit to warn the traffic of the operation that the car is about to make, and after the car has com-

pleted the desired operation, it passes a certain predetermined point wherein the signal is restored to normal and the traffic is permitted to proceed in its usual manner.

5 There are, of course, modifications and arrangements of the parts which may be made from that shown in the above disclosure and which will still fall within the scope of my invention.

10 I claim:

1. In an automatic switch and signal system, the combination of a signal circuit including a signal, an actuating solenoid, a relay operable to selectively direct currents through different parts of the actuating solenoid, and a second relay for controlling the said signal circuit and arranged to be automatically shunted out upon a flow of saturating current through one branch of the said solenoid.

15 2. In an automatic switch and signal system, the combination of a normally open signal circuit, an actuating solenoid, a relay for selectively directing currents through different parts of said actuating solenoid, and a second relay energized through one branch of the said actuating solenoid and arranged to be automatically de-energized upon a flow of saturating current through

20 the said branch of the actuating solenoid.

25 3. In an automatic switch and signal system, the combination of a signal circuit including a signal, an actuating solenoid, a relay operable to selectively direct currents through different parts of the said actuating solenoid, and a second relay being in circuit with one branch of the said solenoid to control the signal circuit and affect the display of the said signal.

30 4. In an automatic switch and signal system, the combination of a signal circuit, a signal, an actuating solenoid, a relay operable to selectively direct currents through different parts of the said actuating solenoid, and a second relay normally in circuit with one branch of the said actuating solenoid and arranged to be shunted out upon a flow of saturating current through the said actuating solenoid to affect the display of the

50 said signal.

45 5. In an automatic switch and signal system, the combination of a signal circuit, a signal, an actuating solenoid, a relay operable to selectively direct currents through different parts of the said actuating solenoid, and a second relay normally energized through one branch of the said actuating solenoid and arranged to be automatically de-energized upon a flow of saturating current

55 through the said branch of the said actuating solenoid, and means to restore the said second relay to its normal condition.

60 6. In an automatic switch and signal system, the combination of a signal circuit, a signal, an actuating solenoid, a relay oper-

able to selectively direct currents through different parts of the said actuating solenoid, and a second relay normally energized through one branch of the said actuating solenoid and arranged to be automatically de-energized upon a flow of saturating current through the said branch of the actuating solenoid and remain de-energized until a restoring means is affected.

70 7. In an automatic switch and signal system, the combination of a signal circuit including a signal, an actuating solenoid, a relay operable to selectively direct currents through different parts of the said actuating solenoid, and a second relay normally energized and in circuit with one branch of the said actuating solenoid, arranged to be automatically de-energized upon a flow of saturating current through the said branch of the actuating solenoid to control the said signal circuit and affect the display of the said signal until a restoring means is effected.

75 8. In an automatic switch and signal system, the combination with a switch point, a double solenoid operating means for the switch point to operate it in one direction or the other and having one side of each solenoid connected to the ground, a signal circuit including a signal, a trolley wire, a contact pan with a pair of parallel contacts to be bridged by a current collector, a solenoid operating circuit from one contact to the solenoids to carry current to operate the solenoids when the current collector engages the pan contacts, a selector switch interposed in said circuit for directing the current to one solenoid or the other at will, and a relay normally in circuit with one of the said solenoids operable upon a saturating flow of current to the said solenoid to affect the said signal circuit.

80 9. In an automatic switch and signal system, the combination with a switch point, a double solenoid operating means for the switch point, to operate it in one direction or the other, a signal circuit including a signal, a trolley wire, a contact pan comprising a pair of parallel contacts to be engaged by a current collector, a solenoid operating circuit from one contact to the solenoids to carry current to operate the solenoids when the current collector engages the pan contacts, a selector switch interposed in said circuit for directing the current to one solenoid or the other at will, and a relay normally energized through one of the solenoids and arranged to be shunted out upon a flow of saturating current to the said solenoid to affect the said signal circuit, and means whereby the said second relay may be stored to normal.

85 10. In an automatic switch and signal system, the combination of a signal circuit including a signal, a trolley wire, an actuating solenoid, a relay operable to selectively direct

current through different parts of the actuating solenoid and a second relay included between the said trolley wire and one branch of the said actuating solenoid to control the said signal circuit upon a saturating flow of current through the branch of the said actuating solenoid.

11. In an automatic switch and signal system, the combination of a signal circuit including a signal, a trolley wire, an actuating solenoid, a relay operable to selectively direct currents through different parts of the said actuating solenoid, and a second normally energized relay included between the said trolley and one branch of the said actuating solenoid and arranged to be automatically de-energized upon a flow of saturating current through the said branch of the actuating solenoid, and means whereby the said second relay remains de-energized to affect the said signal circuit until it is restored to its normal condition.

12. In an automatic switch and signal system, the combination with a switch point, a double solenoid, operating means for the switch point, a signal circuit including a signal, a trolley wire, a solenoid operating contact pan comprising a pair of parallel contacts to be engaged by a current collector, a solenoid operated circuit from one contact to the solenoids to carry current to operate the solenoids when the current collector engages the pan contacts, a selector switch interposed in said circuit for directing the current to one solenoid or the other, a second contact pan mounted in advance of the solenoid operating contact pan, and a relay normally energized through one of the solenoids and in circuit with the said second contact pan so arranged as to be automatically de-energized upon a saturating flow of current to one of the said actuating solenoids, and remain de-energized until the current collector engages the said second contact pan wherein the relay will be restored to its normal condition.

13. In an automatic switch and signal system, the combination of a signal circuit including a signal, an actuating solenoid, a relay operable to selectively direct current through different parts of the said actuating solenoid and a second relay equipped with an armature controlling the contact in said signal circuit, so arranged that the said armature is normally out of contact engagement with the contact but is brought into such contact engagement upon a flow of saturating current to one branch of the said actuating solenoid to effect a display of the said signal.

14. In an automatic switch and signal system, the combination with a switch point, a double solenoid operating means for the switch point, a signal circuit including a signal, a trolley wire, a contact pan comprising a pair of parallel contacts to be engaged by current collector, a solenoid operating cir-

cuit from one contact to the solenoid, to carry current to operate the solenoid when the current collector engages the pan contacts, a selector switch interposed in said circuit for directing the current to one solenoid or the other, means associated with one of the said solenoids affected by flow of saturating current to the said solenoid to cause a signal to be displayed and continues until the said means is operated to restore the system to normal.

In testimony whereof I affix my signature.
FRANK H. RICHTERKESSING.
